[57] CLAIM

The ornamental design for a transcutaneous electrical nerve stimulator, as shown and described.

DESCRIPTION

FIG. 1 is a top, front and side perspective view of a transcutaneous electrical nerve stimulator, showing our new design;

FIG. 2 is a rear elevational view thereof;

FIG. 3 is a side elevational view thereof;

FIG. 4 is a front elevational view thereof;

FIG. 5 is a side elevational view thereof, opposite that shown in FIG. 3;

FIG. 6 is a top plan view thereof;

FIG. 7 is a bottom plan view thereof;

FIG. 8 is a top, front and side perspective view of a second embodiment of the transcutaneous electrical nerve stimulator;

FIG. 9 is a rear elevational view thereof;

FIG. 10 is a side elevational view thereof;

FIG. 11 is a front elevational view thereof;

FIG. 12 is a side elevational view thereof, opposite that shown in FIG. 10;

FIG. 13 is a top plan view thereof; and

FIG. 14 is a bottom plan view thereof.
